MEANS FOR MOUNTING PHOTOGRAPHING DEVICE ON A VOTING MACHINE, OR THE LIKE

Thomas C. Willson, Havertown, Pa., assignor to Shoup Toll Collecting Devices, Inc., Ridley Park, Calif.

Filed Aug. 2, 1960, Ser. No. 52,309

3 Claims. (Cl. 235—50)

This invention relates to a voting machine of the type shown in Shoup Patent No. 2,054,102.

A voting machine of the type referred to includes vote counters which record the total number of votes cast for each of the candidates and, in order to insure against fraud, the vote counters are inspected by watchers for the contending political parties to make sure that the vote counters are set at zero before the electors begin voting, said vote counters being again inspected, after the voting is completed, to ascertain the total number of votes cast for each candidate. The losing candidates sometimes ask for a recount, or charge that the machine was tampered with, and, when such disputes arise, it becomes necessary to examine the voting machines. Because this possibility exists for quite a while after each election, it is the practice to seal and impound the voting machines for the length of time during which a dissatisfied candidate has the right to complain. Sealing and impounding the machines for the purpose stated renders them unavailable for use until the period during which a complaint may be made has expired. Voting machines are expensive, and keeping the middle increases the cost of elections. Furthermore, machines of this type are usually stored in a private, or in a public, warehouse, or other storage facility, and even if a special guard is maintained, there is no assurance that the machines will not be tampered with while in storage. In fact, the mere breaking of a seal on a machine will render the totals shown by the counters of said machine inadmissible in evidence, and this can have very serious results. Also, reference to the voting machines after the election is completed makes it necessary for the election officers to go to the place where the machines are stored, or for the machines to be brought to the offices of the election officers, thus involving inconvenience and expense. To avoid these difficulties, it has heretofore been proposed to photograph the vote counters immediately before the voting has begun, so as to have incontrovertible evidence that the counters were set at zero before any votes were cast, and to photograph the vote counters immediately after the voting has been completed in order to have incontrovertible evidence as to the total number of votes received by each candidate, thus making it unnecessary to seal and impound the machines, and making further reference to the machines unnecessary. Examples of the application of photographic equipment to voting machines are disclosed in the following patents: Petit, No. 1,977,453; Longoria, No. 2,038,302; Petit, No. 2,123,151; Hineline, No. 2,136,262; and Hineline, No. 2,203,906.

Because the expense involved in making a multi-lens camera, and in making a film large enough, and in providing equipment large enough to develop such a large film, is very great, it is not practical to photograph all of the vote counters, which are spread over an area of about 40 inches square, at one exposure. Using a single lens camera, which can only photograph a fraction of the total number of the vote counters at one exposure, is practical but, in order to photograph the counters without overlapping and without missing any, and, in order to provide uniform and clear pictures from which the relatively small numerals on the vote counters can be read, it is necessary that the lens be brought into exact registration with a predetermined number of counters at each exposure, and

2

it is necessary that the distance between the lens and the vote counters is kept constant.

It is therefore one object of this invention to produce improved mounting means which permits rapid movement of the camera into registration with predetermined groups of vote counters while insuring uniform spacing of the lens relative to the vote counters in all positions of the camera.

A further object of the invention is to produce improved 10 mounting means which is light, durable and compact, and which can be instantly applied to, or removed from, the voting machine whereby one camera can be used to photograph the counters of a large number of voting machines.

These and other objects are attained by my invention as 15 set forth in the following specification and the accompanying drawings, in which:

FIG. 1 is a perspective view showing the application of the mounting means of my invention to a voting machine.

FIG. 2 is an enlarged front elevational view of the 20 same.

FIG. 3 is an enlarged view, partly in section and partly in elevation, looking in the direction of line 3—3 on FIG. 2.

FIG. 4 is an enlarged diagrammatic view looking in the 25 direction of line 4—4 on FIG. 2, and showing details of construction of the camera-supporting mechanism, the same being shown in camera-supporting position.

FIG. 5 is an enlarged diagrammatic view looking in the 30 direction of line 5—5 on FIG. 2, and showing the camera-supporting parts in non-supporting position.

FIG. 6 is an enlarged fragmentary perspective view of the camera-supporting mechanism shown in FIGS. 4 and 5.

FIG. 7 is an enlarged fragmentary view looking in the 35 direction of line 7—7 on FIG. 8.

FIG. 8 is similar to FIG. 2, but showing another embodiment of the invention.

FIG. 9 is an enlarged sectional view looking in the direction of line 9—9 on FIG. 8.

40 Since the voting machine illustrated may be conventional, and forms no part of the present invention, it is not shown or described in detail. It is sufficient to point out that 10 designates the front side of the machine, that is, the side which carries voting keys 12 which are operated by the voters, and counters 14 which record the votes cast by the manipulation of the corresponding keys. The voting machine is encased in a housing, which is also immaterial to the present disclosure except for the upper portion 16 thereof, from which the camera mounting means of 50 this invention is suspended.

The camera proper also forms no part of the present invention, and it is therefore neither shown nor described in detail. Instead, it is shown only in outline, and is designated by reference numeral 20.

55 The means for mounting the camera 20 in registration with a predetermined number of vote counters, and for permitting movement of the camera to various selected positions across the face of the voting machine, and from one machine to another, includes two rails 22 and 24 which are provided with oppositely facing guide slots 26 for slidably receiving flanges 28 which project laterally from the opposite sides of the camera casing to guide the latter in its vertical motion relative to the rails.

60 In the embodiment of FIG. 1, the rails, which are braced together by upper and lower cross bars 30 and 31, are suspended from upper portion 16 of the voting machine housing by engaging key hole slots 32, which are formed in upper cross bar 30, with the heads of screws 34 carried by upper housing portion 16.

65 In the embodiment of FIG. 8, the upper housing portion 16 is provided with a track 36 on which rollers 38, which

are carried by upper cross bar 30 of rails 22 and 24, are adapted to ride, as best shown in FIGS. 8 and 9.

The camera positioning and supporting means includes a number of shafts 40, 42 and 44, which are journaled for rotation about their axes in suitable bearings not shown, and each of which fixedly carries a pair of sleeves 46, one adjacent rail 22 and one adjacent rail 24. As will be seen from FIG. 6, each sleeve has a supporting lug 48 which, in a first position, supports the camera, and in a second position, is out of the path of movement of the camera. Each 10 sleeve 46 also has a lug 50 which in said first position abuts rib 52 formed on the inner side of each rail to limit rotation of the shaft, and which in said second position is also out of the way. Each shaft is provided with an operating handle 54, by means of which the shaft is rotated from, 15 and to, said first and second positions.

The operation is as follows:

Before an election is begun, rails 22 and 24, with the camera 20 mounted thereon, are suspended from upper housing portion 16, as shown in FIG. 1, or in FIG. 8. 20 As shown in FIGS. 1 and 2 and 8, the camera is resting on supporting lugs 48 of sleeves 46 on shaft 44, and stop lugs 50 abut ribs 52 to prevent rotation of the shaft in clockwise direction as viewed in FIGS. 4, 5 and 6. In this position, the upper left hand group of vote counters is 25 photographed. To photograph the upper right hand group of vote counters, rails 22 and 24 are moved to the right hand side of the machine. To photograph the central group of counters, shaft 42 is turned to the position of FIG. 4, in which lugs 48 will be in camera supporting 30 position, and shaft 44 is turned to the position of FIG. 5, in which lugs 48 will be out of the way to permit the camera to be lowered until it comes to rest on lugs 48 which are carried by shaft 42. In other words, by moving the rails from right to left and vice versa, and by moving the 35 camera up and down, all of the vote counters can be rapidly and clearly photographed by a limited number of exposures. After the entire side of the machine has been photographed, the rails are detached and the machine is ready for use. At the end of the election, the rails are 40 again applied to the machine and the operation is repeated.

What I claim is:

1. The combination with a voting machine of the type which includes 45
vote recording counters
and a camera for photographing said counters,
said counters covering an area larger than the field of
the camera,
of a supporting device for mounting said camera in 50
registration with various predetermined portions of
said area,
said device including a pair of spaced, vertical rails
providing a track,
means for movably and detachably suspending said rails
from said voting machine in registration with said 55
counters,
said rails having channels formed therein,
means carried by said camera for engaging said channels
slidably to mount said camera on said rails,
shafts journaled for rotation in said rails and disposed 60
substantially normal to said rails,
a pair of stops carried by each of said shafts, one near
each of said rails, and
means for rotating said shafts to move said stops into 65
a first position in which said stops arrest the move-
ment of said camera relative to said rails, and to a
second position in which said stops are out of the
path of movement of said camera,
said stops being so disposed along said rails that the 70
lens of a camera supported by any pair of said stops

will be in focal registration with a predetermined portion of said area.

2. A device for movably and detachably supporting a camera in operative relation to predetermined portions of an object to be photographed,

said object having an area larger than the area of the field of the camera,
said device including a carriage for supporting said camera,

and means for rapidly and selectively juxtaposing said camera in scanning position relative to horizontally or vertically arranged portions of said object, said means including

a pair of spaced vertical rails,

a first complementary inter-engaging means on the sides of said carriage and on the facing sides of said rails mounting said carriage for free sliding movement relative to said rails,

shafts journaled for rotation in said rails and disposed substantially normal to said rails,

a pair of stops carried by each of said shafts, one near each of said rails, and

means for rotating said shafts to move said stops into a first position in which said stops arrest the movement of said camera relative to said rails, and to a second position in which said stops are out of the path of movement of said camera,

said stops being so disposed along said rails that the lens of a camera supported by any pair of said stops will be in focal registration with a predetermined portion of said area.

3. A device for detachably and movably mounting a camera in operative relation to an object to be photographed,

said object having an area larger than the field of said camera,

said device including a vertical frame coextensive with the length of said area vertically considered,

the width of said frame being less than the width of said area, horizontally considered,

mounting means detachably mounting said frame in registration with a selected vertical portion of said area,

means mounting the camera for free sliding relative to said frame, and

stops intermediate the ends of said frame and movable to a first position in which they permit the free movement of the camera from the top to the bottom of said frame,

said stops being movable to a second position in which they limit the movement of the camera relative to said frame,

the width of the frame and the location of the stops being calibrated so that movement of the frame into registration with successive vertical portions of said area brings the field of the camera into registration with non-overlapping, horizontally successive portions of said area and so that limitation of the vertical movement of the camera by said stops brings the camera into registration with non-overlapping, vertically successive portions of said area.
